(57) **CLAIM**

The ornamental design for an assembling game plate, as shown and described.

DESCRIPTION

FIG. 1 is a front view of an assembling game plate of the present invention provided with magnets internally.

FIG. 2 is a rear view of thereof.

FIG. 3 is a top plan view thereof.

FIG. 4 is a bottom plan view thereof.

FIG. 5 is a right side view thereof.

FIG. 6 is a left side view thereof.

FIG. 7 is a perspective view thereof; and,

FIG. 8 is a sectional view thereof taken along section line 8-8 of FIG. 1.

The alternating long and short dashed lines indicate bounds of the claimed design and form no part thereof.

The features shown in broken lines are included to illustrated portions of the assembling game plate and form no part of the claimed design.
